UNITED STATES PATENT OFFICE.

ELMER M. RAY, OF HOMINY, OKLAHOMA.

SWIVEL SOCKET.

Application filed June 25, 1924. Serial No. 722,417.

To all whom it may concern:

Be it known that I, ELMER M. RAY, a citizen of the United States, residing at Hominy, in the county of Osage and State of Oklahoma, have invented new and useful Improvements in Swivel Sockets, of which the following is a specification.

This invention relates to swivel sockets of the character used in well drilling operations, and has for one of its chief characteristics the provision of a device wherein the seat for the movable socket member can be quickly and conveniently removed from the body of the device when it becomes damaged beyond further use, and replaced by a new one at the place where the device is in use, thus eliminating the necessity of taking the device to a machine shop for this purpose.

In carrying out the invention I also provide the body of the device with a plurality of slots and openings, through certain of which the seat can be examined from time to time, and through others of which the bottom of the device can be cleaned as the occasion may require.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view in elevation of the device forming the subject matter of the invention.

Figure 2 is a sectional view taken on line 2-2 of Figure 1.

Figure 3 is a sectional view taken on line 3-3 of Figure 2.

Figure 4 is a sectional view taken on line 4-4 of Figure 2.

Referring to the drawing in detail 10 represents the body of the device which is preferably of cylindrical contour in cross section, except for the reduced squared portion 11 provided to permit the use of a wrench for the purpose of holding the body steady for a purpose to be hereinafter described. It will be noted upon inspection of Figure 2 that the body is formed with a longitudinal bore, divided into upper and

lower portions 12 and 13 respectively, and an intermediate portion 14. The upper portion 12 is relatively small and adapted to receive the operating cable not shown, while the lower portion 13 has a diameter considerably larger than the upper portion 12, and receives the socket member 15, which is arranged in the lower portion 13 of the bore for both sliding and rotatable movement. This member 15 is formed with the usual socket 16 to receive the knotted end of the cable, not shown, or said cable may be associated with the socket member 15 in any well known manner. The bore in the socket member 15 is formed with grooves 17 into which a portion of the cable projects to make a tight fit between the cable and said socket member 15. The lower portion 13 of the bore is interiorly threaded as at 18 to accommodate the particular tool to be used in connection with the body portion 10. The intermediate portion 14 of this bore has a diameter greater than the upper portion 12, but less than the lower portion 13, and is adapted to receive the seat 19 for the socket member 15, which seat is of a size to be snugly fitted within said intermediate portion 14 as clearly shown in Figure 2. The upper end of the socket member contacts the adjacent end of the seat 19, which seat protects the body portion from wear incident to the use of the device.

It will now be noted that the body portion 10 is formed with spaced slots 20 and 21 through which the socket member as well as the cable can be examined from time to time, and through which the seat 19 can also be examined. For this same purpose I provide the body portion 10 with an opening 22 which is arranged at a point approximately midway between the ends of the seat 19 when the latter is in its normal condition. When the seat has become worn so that the lower end of the seat can be seen through the opening 22, the said seat can be easily and quickly removed, and replaced by a new seat without the necessity of carrying the device to a machine shop for this purpose. In other words this work can be accomplished at the place where the device is being used, as it is only necessary to support the body 10 by a wrench which is used in conjunction with the squared portion 11 of the body portion and above referred to. After the wrench has been placed on the body portion 10, the cable

above referred to is slackened to allow the socket member 15 to be lowered beyond the lower end of the body portion 10, after the tool above referred to has been separated 5 from the body portion. Then any suitable instrument can be inserted through the opening 22 to force the worn seat 19 from the intermediate portion 14 of the bore, into the larger lower portion 13 thereof, through 10 which it will readily fall to the open end of the body portion. The body portion is also formed with an opening 23 adjacent the lower end thereof which is used for the purpose of cleaning the body portion 10 as 15 the occasion may require.

While it is believed that from the foregoing description, the nature and advantages of the invention will be readily apparent, I desire to have it understood that I do not 20 limit myself to what is herein shown and described, and that such changes may be resorted to when desired as fall within the scope of what is claimed.

What I claim is:

25 A device of the character described comprising a body portion having a longitudi-

nal bore threaded and slightly tapered adjacent the lower end thereof, the opposite sides of the body portion for an appropriate part of its length being flattened to accommodate a tool for turning said body portion, said bore being divided into upper and lower portions of relatively different diameters, and an intermediate portion of slightly less diameter than the lower portion, and slightly greater than the upper portion, a socket member slidably and rotatably fitted in the lower portion of said bore, a seat snugly fitted within the intermediate portion of the bore and adapted to be engaged by the 40 socket member, said seat being capable of being removed from the body portion through the lower end of said bore, said body portion having sight openings at the opposite sides through which said end socket member can be examined, said socket having a longitudinal bore formed with spiral 45 grooves to provide for an effective grip on the cable for the socket member.

In testimony whereof I affix my signature.

ELMER M. RAY.
